UNITED STATES PATENT OFFICE.

CHARLES H. WATTS, OF NORTH BRADDOCK, PENNSYLVANIA.

HYDRAULIC PACKING-SHIELD.

1,073,550.

Specification of Letters Patent. Patented Sept. 16, 1913.

Application filed October 11, 1912. Serial No. 725,186.

To all whom it may concern:

Be it known that I, CHARLES H. WATTS, a citizen of the United States of America, residing at North Braddock, in the county 5 of Allegheny and State of Pennsylvania, have invented certain new and useful Improvements in Hydraulic Packing-Shields, of which the following is a specification, reference being had therein to the accompanying drawing.

This invention relates to a hydraulic packing shield, and more particularly to a metallic shield for packing used in connection with piston heads and other movable bodies 15 for establishing a non-leakable connection between the movable and stationary bodies.

The primary object of my invention is to provide a sectional telescopic channel-shaped yieldable metallic shield made of 20 copper or other anti-frictional metal that will readily accommodate itself to packing and support and prevent undue wear, deterioration and breaking down of packing.

Another object of this invention is to provide a yieldable shield for hydraulic packing that has provision for the expanding of packing by water pressure, without the water circulating in the shield.

A further object of this invention is to 30 provide an expandible shield that can be used in connection with leather, rubber, hemp or other stand packing material.

A still further object of this invention is to accomplish the above results by a mechanical construction that is inexpensive to 35 manufacture, durable, easy to install, and highly efficient for the purposes for which it is intended.

With the above and other objects in view 40 the invention resides in the novel construction, combination and arrangement of parts to be hereinafter specifically described and then claimed.

Reference will now be had to the drawing 45 wherein like numerals denote corresponding parts throughout the several views, in which:

Figure 1 is a longitudinal sectional view of a portion of a cylinder and piston illustrating the shield in connection therewith, 50 Fig. 2 is a perspective view of a portion of the shield, Fig. 3 is a similar view of another portion of the shield, Fig. 4 is a perspective view of the shield.

The reference numeral 1 denotes a stationary body, as a cylinder and movable in

this cylinder is a piston rod 2 having removable piston sections 3 and 4 and a follower head 5, said head being attached to the piston section 3 by screw bolts 6 and said piston sections and said head held upon the reduced end of said piston rod by a nut 7. The piston sections 3 and 4 have the peripheral edges thereof provided with annular recesses 8 and communicating with these recesses are openings 9 in the piston section 4 and openings 10 in the follower head 5, these openings permitting of water pressure entering the recesses 8 to expand the contents of said recesses, besides preventing the circulation of water within said recesses. Located in each recess is a shield containing packing, each shield comprising three non-corrodible metallic telescopic channel-shaped sections 11, 12 and 13. An end 75 of each section has a pin 14 that extends into a longitudinal slot 15 formed in the end of an adjoining section. It is preferable to arrange the sections 11, 12 and 13 with telescopic or overlapping ends and with a slot in one end of a section and a pin at the opposite end of the section. It is obvious that one end of the section will extend over an adjoining section and the other end of the same section under an adjoining section. 80 By this arrangement there is a continuous channel within the sections capable of holding packing 16, the packing projecting from the edges of the sections to present a wearing surface 17, and rings 18 of leather or 85 suitable material can be arranged at the edges of the sectional shield whereby the shield and packing will snugly fit within the recess 8.

The walls of the shield confront the piston sections 3 and 4 and which could therefore be termed the inner walls, or concave, as shown in Figs. 2 to 4 inclusive and when pressure is brought to bear upon the wearing surface 17 of the packing, the inner 90 walls of the shield tend to flatten and thereby force the side walls of the shield into engagement with the packing, to brace and maintain the same in form while such pressure is exerted.

It is to be understood that no packing glands are necessary and that the packing rings are made to fit the bore of the cylinder and the shields adjusted before being placed in the recesses of the plunger or piston. The 100 shields are retained in position by the follower head and the piston sections without 105

any strain upon the shields. The ends of the shields can be connected with or without slots and pins and in some instances the concave walls of the shield can be dispensed with.

It is thought that the operation and utility of the shield will be apparent without further description, and while in the drawing there is illustrated a preferred embodiment of my invention it is to be understood that the structural elements are susceptible to such changes, as in size, shape and manner of assemblage as fall within the scope of the appended claims.

15. What I claim is:

1. A piston packing shield comprising non-corrodible metallic channel-shaped telescopic expandable sections capable of supporting packing, the inner wall of each of said sections capable of being flattened.

2. A piston packing shield comprising non-corrodible metallic channel-shaped telescopic expandable sections having concave inner walls capable of being flattened.

25. 3. As a new article of manufacture, a piston packing comprising a shield formed of a plurality of telescopic channel-shaped sections, and means for interlocking the ends of said sections together.

30. 4. A piston packing comprising in combination, a shield in the form of an annulus and consisting of a plurality of channel-shaped telescopic sections adjustably connected together, packing mounted in and projecting from said shields, and rings mounted upon said packing and abutting against the edges of said sections.

5. A piston packing comprising in combination, an adjustable shield in the form of 40 an annulus consisting of a plurality of channel-shaped sections, the inner wall of each of said sections being concave, the inner wall of one section resting upon the inner wall

of an adjacent section, said inner wall of each section capable of being flattened thereby forcing the side walls of each section toward each other.

45. 6. A piston packing comprising in combination, an adjustable shield in the form of an annulus consisting of a plurality of channel-shaped sections, the inner wall of each of said sections being concave, the inner wall of one section resting upon the inner wall of an adjacent section, said inner wall of each section capable of being flattened thereby forcing the side walls of each section toward each other, and means for interlocking the sections together.

50. 7. A piston packing comprising in combination, a shield formed of a plurality of telescopic interlocked sections, and packing mounted in said sections.

55. 8. A piston packing comprising in combination, a shield formed of a plurality of telescopic interlocked sections, packing mounted in said sections and projecting therefrom, and rings mounted upon the projecting portion of the packing and abutting against the edges of said sections.

60. 9. A piston packing comprising in combination, a shield formed of a plurality of telescopic interlocked sections, packing mounted in said sections and projecting therefrom, and rings mounted upon the projecting portion of the packing and abutting against the edges of said sections, the inner wall of each of said sections being concave and capable of being flattened whereby the side walls will be caused to grip the packing.

70. In testimony whereof I affix my signature in the presence of two witnesses.

CHARLES H. WATTS.
